UNITED STATES PATENT OFFICE.

WALTER I. OESCHGER, OF DETROIT, MICHIGAN.

PRIMING-COCK.

1,252,157.

Specification of Letters Patent. Patented Jan. 1, 1918.

Application filed March 28, 1917. Serial No. 157,910.

To all whom it may concern:

Be it known that I, WALTER I. OESCHGER, a citizen of the United States, and residing at Detroit, in the county of Wayne and State of Michigan, have invented a new and Improved Priming-Cock, of which the following is a specification.

This invention relates to priming cocks adapted for the cylinders of internal combustion engines and to other machinery to which small amounts of liquids are to be conveyed at intervals, and its object is to provide a construction of this character which shall be strong and durable, easily attached and detached, and which can be manufactured at low cost.

This invention consists of a cock having a body formed with a polygonal end, a sheet metal cup secured to said end, a tapering plug revolvable in said body and means to hold the plug in proper position. It further consists in forming notches in the body, mounting a detented washer on the plug, and mounting a spring on the plug to press the washer against the body in order to hold the plug in one or another predetermined position. It also consists in a novel slip washer adapted to engage the end of the plug and to be held in place by said end for the purpose of forming an abutment to hold the spring in proper position.

In the accompanying drawing, Figure 1 is an elevation of this priming cock. Figs. 2 and 3 are elevations of the body of the cock at right angles to each other. Fig. 4 is a plan of this body. Fig. 5 is an elevation of that portion of the body which is provided with notches to receive the detents on a washer. Figs. 6 and 7 are elevations at right angles to each other of the detent washer on twice the scale employed on Figs. 1 to 5 inclusive. Fig. 8 is a plan of this washer, Fig. 9 is a bottom plan, Fig. 10 is an elevation and Fig. 11 is a plan of the cup portion of the priming cock on the same scale as Figs. 1 to 5 inclusive. Figs. 12 and 13 are views at right angles to each other of the plug on the same scale as Figs. 6 and 7. Fig. 14 is an end view thereof taken from the left in Fig. 12. Fig. 15 is an elevation and Fig. 16 a horizontal section of the washer to hold the spring on the shank of the plug.

Similar reference characters refer to like parts throughout the several views.

The ultimate form of the present priming

cup is shown to be much the same as those now on the market, but the details thereof are such as to make it possible to produce this cock at a much lower cost of manufacture and to render it more easily attached and detached. The plug is what might be said to be a screw machine job as the body thereof will be formed practically entirely on a screw machine from a round metal rod, preferably steel. The plug will also be formed on a screw machine from a round rod, preferably of brass. The cup shown in Figs. 9, 10 and 11 is a stamping, as are also the two washers. The spring is wound in the usual manner from round wire.

The body 1 of the cock is threaded at its lower end 2, is formed polygonal at its opposite end 3, is provided with a usual longitudinal passage 4, has the tapering hole 5 to receive the plug and has that portion around the small end of the hole 5 flattened and formed with notches 6. In manufacturing this body the end 3 will be formed round and after the body is cut off from the rod from which it is turned, it is placed in a press having a solid die that shaves down the end 3 to its desired form. In order to render this possible a small groove 7 is cut into the body as indicated in Figs. 2, 3 and 5 at the base of this end 3 to permit the chips produced by the die to break away.

The cup 10 shown in Figs. 9, 10 and 11 is pressed out of a disk of sheet metal, preferably mild steel, and formed with the shank 11 that fits the end 3 of the body of the plug. After the cup is in place a special tool is employed to press down the upper edges of this end 3 onto the pocket-like depressions in the lower portion of the cup 10, as shown at 13 in Fig. 1, in order to secure the cup to the body of the cock. In practice it is thus possible to form the body from a rod three-fourths of an inch in diameter and to secure a cup 10 of several times that diameter to this body at very small cost of material.

The plug is formed with a tapering portion 14 adapted to fit the hole 5 in the body, which portion has a transverse passage 15. The plug has a head 16 provided with a hole 17 preferably at an oblique angle to the body of the plug, into which hole the handle 18 is fitted. The shank 19 of the plug has a flat side 20 and a circumferential groove 21 near its end. A washer 22, having a hole 23 into which the shank 19 will slidably fit and a pair of detents 24, is placed on this

shank with the detents toward the body 1 of the cock in order that they may engage in the notches 6. A spring 25 is placed on the shank 19 in engagement with the washer 22. The second washer 26 has a transverse slot 27 of such a width that it will admit the reduced portion 28 of the shank of the plug and a circular depression 29 to receive the flange 30 at the end of the plug. If desired, the washer may be formed with the circumferential groove 31 to receive the spring.

The handle 18 is secured in position in the plug, after which the plug is slipped into the hole 5 of the body 1. The washer 22 is then positioned, after which the spring is placed on the shank 19 and compressed sufficiently to slide the washer 26 into position. The groove 21 around the lower end 20 of the shank 19 is sufficiently wide to permit the grooved outer annular portion of the washer 26 to pass through it. After the washer 26 is concentric with the shank the spring will push it outwardly until the head 30 of the shank is in the depression 29 of the washer and thereby holds the washer in position on the shank and prevents it from slipping out of place. The outward thrust of the spring on the washer will prevent its displacement. The detents 24 on the washer 22 will serve to hold the plug in fully open or fully closed position. These detents may be omitted if desired in which case the shank 19 will be left cylindrical and the washer 22 will be formed with a circular hole.

By forming the upper end of the body and the part 11 of the cup polygonal, preferably hexagonal, an engaging surface for wrenches is provided at such a distance from the threaded end 2 of the cock that attaching and detaching of the cock from the engine is greatly facilitated. The ordinary cock is now formed with its hexagon between the plug and the threaded end, because the

body of the cock is usually made of brass which is so brittle that the position of this hexagonal portion adjacent the threaded end is substantially imperative. But when the body of the cock is formed of steel, this consideration no longer exists and the hexagon can be formed at the opposite end of the cock which is the most convenient point.

I claim:

1. In a priming cock, the combination of 55 a body having one end threaded and the opposite end formed polygonally, a cup having a polygonal shank to engage the polygonal end of the body, said body having a transverse tapering hole intermediate its 60 ends and longitudinal passages extending from said tapering hole to its ends, a plug provided with a transverse passage and fitted into said tapering hole, and means to hold said plug in position.

2. In a priming cock, the combination of 65 a body having one end polygonal in cross section, a sheet metal cup having a polygonal shank fitting around the polygonal end of the body, said body having a transverse tapering hole intermediate its ends and longitudinal passages extending from said tapering hole to its ends, a plug provided with a transverse passage and fitted into said tapering hole, and means to hold said plug in 70 position.

3. In a priming cock, the combination of 75 a body having one end threaded and the opposite end formed polygonally, a cup having a polygonal shank of less length than 80 the polygonal portion of the body, said shank fitting over the polygonal portion of the body and the outer end of the polygonal portion of the body being expanded to hold the cup in position, said body being formed 85 with a longitudinal passage and a transverse hole, and a plug in said hole to open and close the passage.

WALTER I. OESCHGER.
